SURGICAL SUTURE REMOVER

William Glenn Allen, Jr., 1811 Floyd Ave.,
Richmond, Va. 23220

Filed Nov. 30, 1973, Ser. No. 420,555

Term of patent 14 years

Int. Cl. D24—02

U.S. CL. D83—12 R

FIG. 1 is a perspective view of a surgical suture remover showing my new design;

FIG. 2 is a cross-sectional view taken on line 2—2 of FIG. 1;

FIG. 3 is a cross-sectional view taken on line 3—3 of FIG. 1; and

FIG. 4 is a fragmentary view taken from the lower left hand portion of FIG. 1.

I claim:

The ornamental design for a surgical suture remover, as shown.
